Primary Examiner — Jonathan J Han*Assistant Examiner* — Amanda J Berlinski(74) *Attorney, Agent, or Firm* — Marshall A. Lerner; Steven J. Kim; Kleinberg & Lerner, LLP(57) **CLAIM**

The ornamental design for a shoe upper, as shown and described.

DESCRIPTION

FIG. 1 is a left side rear perspective view of a shoe upper in accordance with my new design;

FIG. 2 is a right side rear perspective view;

FIG. 3 is a left side elevation view; and,

FIG. 4 is an enlarged rear elevation view.

The broken lines shown in the drawings represent portions of the shoe upper and environmental structure that forms no part of the claimed design. The surfaces devoid of shading lines are not claimed.
